UNITED STATES PATENT OFFICE.

MOTT C. RUSSELL, OF ASSYRIA, MICHIGAN.

COMBINED DROPPING BOARD AND ROOST.

Application filed April 20, 1923. Serial No. 633,414.

To all whom it may concern:

Be it known that I, MOTT C. RUSSELL, a citizen of the United States, residing at Assyria, in the county of Barry and State of Michigan, have invented certain new and useful Improvements in Combined Dropping Boards and Roosts, of which the following is a specification.

This invention relates to a combined dropping board and roost, and more particularly to such a device in which the dropping board may be tilted when the roost is not in use so as to make available the floor space beneath the same for scratching purposes.

The invention has for its object the provision of a combined dropping board and roost, which will be economical of the space occupied in a chicken house. Another object is the provision in such a device of a pivoting and tilting dropping board, which may be moved into an inclined position by an attendant, so that the space below it may be made available for scratching purposes, and which may be returned to its normally useful position by the chickens when they go to roost. Another object of the invention is the production of an article of chicken house equipment, which will be economical of the space occupied, which may be easily moved from place to place, and which may be readily cleaned.

Other objects and advantages of the invention will hereinafter appear in the following description and the novel features thereof will be particularly pointed out in the appended claims.

Like reference characters indicate like parts throughout the several figures of the drawings, in which—

Figure 1 is a perspective showing my invention in its normally useful position,

Figure 2 is a section through the same while in this position, and

Figure 3 is a similar section with the dropping board in its position to permit the use of the floor space beneath it for scratching purposes.

While I have shown and described my preferred form, it will be understood that the invention may be embodied in other forms and that the details of construction thereof may be changed within the scope of

the appended claims without departing from the spirit of the invention. 55

My invention may be said to comprise a supporting framework and a dropping board carrying perches mounted in said framework in a pivotal and tilting manner. These two elements will now be described in detail, after which a recital of their joint use will be given. 60

The supporting framework has a back 10 to the ends of which standards 11 are suitably secured. To the back and standards are secured the forwardly projecting foot portions 12. It will be understood that the lower edges of the back and foot portions are adapted to rest upon the floor of a chicken house or the like, and constitute the base of the supporting framework of my invention. Suitably secured to the ends of each of the foot portions are uprights 13 and 14, which are joined at their upper ends by the short connector 15. At the upper end of the standard 11 is a short cross piece or stop 16. It will be understood that all of the parts just described are designed to be rigidly connected together to constitute the supporting framework for the dropping board and roost. 70 75 80

Pivoted to the connector 15 is a depending stirrup 17 designed to swing in the plane of and between the two uprights 13 and 14. Between the lower ends of these stirrups the dropping board 18 is pivoted as at 19. The dropping board carries a series of perches or roosts 20, 20, preferably connected by strips 21, which in turn are hinged at the back to the dropping board so that the roost may be lifted from the dropping board when it is desired to clean the same. At the forward end of the dropping board is a gutter 22, in which the droppings which have accumulated may be drawn, and an opening 23 is provided, preferably centrally, for the purpose of removing said droppings from the gutter into a receptacle for disposal. 85 90 95

The operation of my invention will now be described, reference being had to Figure 2, in which the device is shown in its normal or useful position, and to Figure 3, in which the device is shown in its idle position. After the chickens have left the roost in the morning, the dropping board may be cleaned, as hereinbefore described, by lifting 100 105

the roosts and drawing the droppings into the gutter 22 and through the opening 23 into any suitable receptacle. The roosts are then replaced, and the board is drawn forward slightly, sufficient to remove its rear edge from the upper edge of the back 10, when the rear portion of the dropping board will be lowered until it rests upon the floor of the chicken house in close proximity to the lower edge of the back 10. This is accomplished by locating the pivots 19 so that there will be slightly greater weight to the rear thereof than forward. In its descent the board will be guided by the standards 11. The device will then be in the position shown in Figure 3, where the front edge of the dropping board is shown elevated above the floor, and the space beneath the dropping board made available for scratching purposes for the chickens.

In the evening, when the chickens go to roost, several of them will first locate upon the roost or perch marked 20', it being the instinct of chickens to seek the highest point 25 they can reach when roosting. The weight of these chickens will cause the front end of the dropping board to be depressed and the rear edge elevated, and when the rear edge of the dropping board is lifted sufficiently 30 to come into contact with the cross pieces 16, it will come to rest except for a slight backward movement. This backward movement will cause the rear edge of the dropping board to overlie the upper edge of the back 35 10 and to rest thereon when the chickens have advanced from the roost 20' to those at the rear of the dropping board.

It will be seen that I have provided a combined dropping board and roost, which 40 is very economical of the floor space in the chicken house.

Having described my invention, what I claim as new and desire to secure by Letters Patent of the United States is:

1. In a combined dropping board and roost, a support comprising a pair of uprights, a dropping board pivotally mounted between said uprights, and a support for the rear edge of said dropping board, said dropping board being mounted to move 45 bodily toward and from said support, whereby its rear edge may be brought to rest upon said support or upon the floor.
2. In a combined dropping board and roost, a supporting framework comprising a back and uprights, a dropping board pivotally mounted between said uprights and movable toward and from said back, whereby its rear edge may be brought to rest upon the upper edge of said back or upon the 50 floor.
3. In a combined dropping board and roost, a supporting framework comprising a back board and foot portions secured together, uprights from said foot portions 55 connected together at their upper ends, stirrups pivotally suspended from the connected ends of said uprights, and a dropping board pivoted to the lower end of said stirrups and movable so that its rear edge 60 may rest upon the upper edge of the back board or upon the floor.
4. In a combined dropping board and roost, a supporting framework comprising a back and uprights, a dropping board, 75 means for suspending said dropping board from said uprights to give to said dropping board a compound pivotal movement, and means for limiting the pivotal movement of the rear edge of said dropping board.

In testimony whereof I affix my signature.
MOTT C. RUSSELL.
